COAT HANGER

Ray Patrick, Zilwaukee, Mich.

Application March 5, 1949, Serial No. 1,247

Term of patent 14 years

(Cl. D33—8)

To all whom it may concern:

Be it known that I, Ray Patrick, a citizen of the United States of America, and a resident of Zilwaukee, in the county of Saginaw and State of Michigan, have invented a new, original, and ornamental Design for a Coat Hanger, of which the following is a specification, reference being had to the accompanying drawing, forming part thereof.

In the drawing:

Fig. 1 is a front-elevational view of my coat hanger.

Fig. 2 is a top, plan view thereof.

Fig. 3 is a fragmentary transverse-sectional, perspective view taken on the line 3—3 of Fig. 1.

I claim:

The ornamental design for a coat hanger, as shown.

RAY PATRICK.
